TWO-CYCLE GAS ENGINE

Original Filed Nov. 3, 1927 2 Sheets-Sheet 2

Fig. 6

UNITED STATES PATENT OFFICE

WILLIAM E. EWART, OF SEATTLE, WASHINGTON

TWO CYCLE GAS ENGINE

Application filed November 3, 1927, Serial No. 230,735. Renewed October 6, 1930.

The invention is an internal combustion engine having two combustion chambers in a stationary cylinder, one combustion chamber being between the head of the cylinder and the end of a movable hollow piston forming a movable cylinder, and another combustion chamber in the movable cylinder and between the head thereof and a movable piston therein; and an enlarged skirt depending from the end of the movable cylinder forming a piston in a larger or scavenger cylinder; and a crankshaft having three throws or cranks, the center of the two outside cranks which are connected to the movable cylinder being in line and the center of the third or center crank which is connected to the movable piston in the movable cylinder is offset approximately 150 degrees from the center of the two outside cranks.

The invention is an improvement over my prior Patent, No. 1,563,733 which was issued December 1st, 1925 in that the crankshaft connections are offset, the intake and exhaust ports arranged to regulate the flow of the gases with the connecting rods in the offset position, and auxiliary tanks and connections shown between the scavenger cylinder and the intake or exhaust ports.

The object of the invention is to obtain the maximum amount of power with the minimum amount of weight and space.

Another object of the invention is to provide a combination cylinder having two combustion chambers with a movable hollow piston and an inner movable piston, with the pistons connected to opposite sides of a crankshaft in which the throws to the crankshaft are offset so that they are not directly opposite.

Another object of the invention is to provide a combination internal combustion engine having a movable cylinder forming a movable piston within a cylinder in which the ports are arranged to permit intake and exhaust to both cylinders.

Another object of the invention is to provide a two cycle internal combustion engine having two explosion chambers with means for forcibly feeding gas into the cyl-

inders or forcibly drawing the burnt gases out of the cylinders.

A further object of the invention is to provide a combination cylinder for internal combustion engines having a movable cylinder forming a piston within a cylinder and also a movable piston in the movable cylinder in which there are two explosion chambers which explode alternately.

And a still further object of the invention is to provide suitable intake and exhaust ports in the walls of a combination internal combustion engine to permit compression and explosion in two individual chambers.

With these ends in view the invention embodies an internal combustion engine cylinder having a movable inner cylinder forming a piston with an inner movable piston within the said movable cylinder and in which the inner movable piston and movable cylinder are eccentrically connected to opposite sides of a crankshaft and the intake and exhaust ports arranged to permit the passage of the gases at the proper periods. The cylinder is also provided with an enlarged cylinder forming a scavenger cylinder which is connected to a tank through suitable valves to cause a vacuum in the tank and the tank is connected to the exhaust ports of the cylinders so that it will instantly draw the burnt gases out and a fresh charge in. The connections of this tank may be reversed so that compression will be created in the tank to blow the burnt gases out and the fresh charge in. Jets may also be provided in the cylinders through which the fresh charge may be blown into the cylinders under pressure.

Other features and advantages of the invention will appear from the following description, taken in connection with the drawings, wherein:

Figure 1 is a vertical section through the center of the cylinder showing the inner movable piston and movable cylinder in the position in which the explosion occurs, and the outer cylinder and piston in the recharging and exhausting position.

Figure 2 is a similar section with the po-

sitions of the pistons and cylinders reversed.

Figure 3 is a side view of the combined movable cylinder and movable piston showing the positions of the connecting rods with the movable cylinder in the position shown in Figure 1.

Figure 4 is a view showing the positions of the connecting rods at which point both the movable cylinder and inner movable piston begin to travel in the same direction while recharging and exhausting.

Figure 5 is a similar view with the pistons at the end of the compression stroke and in the position in which the explosion 15 in the upper or outer cylinder is about to take place.

Figure 6 is a cross section showing part of the cylinder with a vacuum tank connected to the exhaust ports of the cylinders 20 and to the scavenger cylinder.

Figure 7 is a similar view showing the tank on the opposite side of the cylinder and connected to the intake ports and arranged so that air will be compressed in 25 the tank.

Figure 8 is a section similar to that shown in Figure 2 in which injectors are shown to inject fuel into the cylinders.

Figure 9 is a similar section on a different 30 plane to that of Figure 8 showing the position of the pistons reversed as shown in Figure 1.

In the drawings the cylinder is shown as it would be made wherein numeral 1 indicates the large or outer cylinder, numeral 2 the scavenger cylinder, numeral 3 the movable cylinder forming the movable piston and numeral 4 the inner movable piston.

40 The cylinder 1 may be made in an individual unit or in a cylinder block or in combination with as many other cylinders as may be desired. In the design shown it is provided with a head 5 in the center of 45 which a spark plug 6 may be placed and in the walls thereof are openings 7 and 8 forming intake and exhaust ports and to which suitable headers may be attached as may be desired. The intake port 7 forms a common intake for the cylinder 1 as shown in Figure 1 or for the movable cylinder as shown in Figure 2. Below the port 7 is a spark plug 9 which will co-operate with the opening in the piston 2 as shown in Figure 51 to explode the gases in the movable cylinder. At the lower end of the cylinder 1 is an enlarged portion in which the scavenger cylinder 2 is formed. This cylinder is provided with a port 10 which may be 60 connected to a reservoir 11 which may be of any suitable type and the reservoir may be connected to the intake ports as shown in Figure 7 so that compressed air and fuel from the reservoir may be admitted to the 65 explosion chambers of the cylinders and the

burnt gases forced out by the incoming charge.

The piston of the scavenger cylinder 2 is formed by a skirt or outstanding flange 12 at the lower end of the piston 3 and the connecting rods 13 and 14 of the piston 3 are mounted on wrist pins 15 in hubs 16 in the skirt 12. The opposite ends of the rods 13 and 14 are connected to a crankshaft 17 through hubs 18 as shown.

The piston 3 is made as shown with a chamber 19 in the head and an exterior opening 20 through which fuel is admitted from the port 7 as shown in Figure 2 and also through which the gas is ignited by the spark plug 9 as shown in Figure 1. Below the chamber 19 is a cylinder 21 in which the inner movable piston 4 is slidably mounted. The walls of the cylinder 21 extending downward from the head of the piston 3 may be provided with water-jackets as shown and at the lower end is the flange 12 which forms the piston of the cylinder 2. The piston 3 is provided with an upper set of piston rings as indicated by the numeral 22 and also a lower set 23 which are below the opening 20 so that the piston is sealed on both sides of the intake port. The piston 4 may also be made as shown and attached to the crankshaft 17 at a point approximately 150 degrees from the point at which the rods 13 and 14 of the movable cylinder are connected, through a connecting rod 24 having a hub 25 at the lower end. The wall of the movable 100 cylinder 21 is provided with exhaust openings 26 which co-operate with a circular recess 27 in the wall of the cylinder 1 to permit gases of the inner movable cylinder to exhaust when the cylinder is in the position shown in Figure 2. The recess 27 is provided with an outlet opening 28 which may be connected to an exhaust header or any other suitable device. The piston 3 is provided with a baffle 29 against which the in-coming gases through the port 7 will strike and be deflected upward as indicated by the arrows in Figure 1.

In the design shown in Figure 6 the port 10 of the cylinder 2 is shown as opening into a chamber 30 which may be made integral with the cylinder or bolted to it as shown with the exhaust port 28 opening into it through an opening 31 and the exhaust port 8 opening into it through an opening 32. The port 10 opens into a chamber 33 between valves 34 and 35 and below the valve 35 is an outlet chamber 36 as shown. The stem 37 of the valve 35 is enlarged as shown and provided with a circular opening 38 through which the stem 39 of the valve 34 passes. The stem 39 is provided with a shoulder 40 which engages the upper end of the valve 35 to force it open as shown. The lower end of the valve stem 39 is held 130

in a sleeve 41 by nuts 42 and the lower end of the sleeve is provided with a roller 43 that engages a cam 44 on a cam shaft 45 which is rotated by gears 46, 47 and 48 from the crankshaft 17. The sleeve 41 is resiliently held downward by a spring 49 and the valve stem 37 of the valve 35 is resiliently held upward by a spring 50 which is somewhat smaller than the spring 49. It will be observed that as the piston formed by the skirt 12 moves upward from the position shown in Figure 6 it will force gases in the cylinder 2 out through the valve 35 and as the piston reaches the top of the stroke the cam 44 will close the valve 35 and open the valve 34 so that as the piston moves downward it will draw air or gases from the chamber 30 and as it continues to operate it will create a vacuum therein. The cylinder 2 may be of such a size that it will have a greater displacement than the area of the two cylinders so that a partial vacuum will be maintained in the chamber 30 continuously.

In the design shown in Figure 7 the chamber 30 is positioned on the intake side of the cylinder with the opening 32 connected to the intake port 7 and the opening 31 omitted. In this design the opening 36 may be connected to a carburetor or any suitable gasoline supply and with the action of the valves reversed the cylinder 2 will maintain compression in the chamber 30. The vapor in the chamber 30 will therefore be under pressure so that it will instantly force the burnt gases out of the exhaust ports at the opposite sides and fill the cylinders with a fresh charge.

It is understood that although the cam shaft 45 is shown as being rotated by gears it may be rotated from the crankshaft by any other suitable means.

In the design shown in Figures 8 and 9 the inlet port 7 is omitted and injectors 51 and 52 inserted in the sides of the cylinder and it will be observed that as the exhaust ports are closed by the positions of the pistons the injectors will force fuel under pressure into the cylinders to instantly fill them.

These sections are taken on different planes so that the injectors will not be in the same plane and therefore will not correspond with the intake ports and therefore the injector of one cylinder will not correspond with the intake port of the other cylinder. The injectors may be connected to a compressor as indicated by the numeral 53 which may be operated by any suitable means and located at any suitable position. The connection 54 between the compressor 53 and the injector may be provided with a valve 55 in which the stem extends downward and is operated by another cam 44 on the cam shaft 45. It is also understood that any other suitable

means may be used for injecting or forcing a fresh charge into the cylinders.

It will be understood that changes may be made in the construction without departing from the spirit of the invention. One of which changes may be in the exact angle at which the connecting rod of the inner movable cylinder is connected to the crankshaft in relation to the connecting rod of the inner movable piston. Another may be in the design of the inner or outer movable pistons, another may be in the use of other means for controlling the intake and exhaust and still another may be in the use of other means for connecting the pistons to the crankshaft.

The construction will be readily understood from the foregoing description. In use the device may be assembled as shown with the inner movable cylinder forming a piston within the outer cylinder and with a combustion chamber between the end of the movable cylinder and inner end of the outer cylinder, and an inner movable piston within the movable cylinder forming another combustion chamber between the end of the inner piston and the inner end of the movable piston, with both the inner movable piston and movable cylinder connected to a common crankshaft at opposite sides thereof and with the throw of the inner movable piston approximately 150 degrees from the throw of the movable cylinder so that they are not directly opposed; and the cylinders provided with ports arranged so that fuel may be admitted or forced into the two cylinders, and the exhaust permitted to escape, blown out by the incoming charge, or drawn out by a vacuum; or all of the various arrangements may be used in combination with the vacuum chamber drawing out the burnt gases, the compression chamber forcing air into the cylinder to thoroughly cleanse it, and an injector forcing the fresh charge in after the intake and exhaust ports have been closed by movement of the piston and cylinder; in which instance the vacuum may be created by the scavenger cylinder of one cylinder of an engine, the compression by the scavenger cylinder of another cylinder, and the injection by an auxiliary compressor, or either the vacuum or compression formed by an auxiliary pump or compressor. When it is in the position shown in Figure 1 air will be admitted through the intake port and exhausted through the exhaust port of the upper or larger cylinder and after all gases are exhausted a fresh charge may be injected, while at the same time the fuel will be compressed in the inner movable cylinder 21 and as it arrives at the position shown this fuel will be ignited and as it explodes it will force the piston 4 downward and the cylinder 21 upward so that the piston 4 will exert a downward pressure on one side of the

crankshaft while the cylinder 21 exerts an upward pressure on the opposite side and then as the piston and cylinder arrive at the positions shown in Figure 2, air will be admitted to the cylinder through the port 7 and when the exhaust gases are forced out through the exhaust port 28 a fresh charge will be injected, and at the same time as it arrives at this position the spark plug 6 will 10 ignite the gases in the cylinder 1 and as they explode they will force the piston 3 downward which will exert a downward pressure on the crankshaft. It is understood that any of the various means for injecting a fresh 15 charge of fuel or exhausting the burnt gases may be used in combination with the engine cylinder having an inner movable piston with an opening forming a cylinder therein and an inner movable piston in the said movable cylinder, the most preferred arrangement being a combination of the designs 20 shown in Figures 7, 8 and 9 in which the compression of the scavenger cylinder forces the burnt gases out and as soon as the cylinder is clean and the pistons have moved so that the exhaust and intake ports are closed the injector, which is connected to the auxiliary compressor, injects the fresh charge of fuel into the cylinder. This assures a clean 25 cylinder after each explosion. The vacuum chamber shown in Figure 6 may also be combined with the jets shown in Figures 8 and 9 so that the burnt gases will be drawn out by the vacuum and then as soon as the pistons have moved to close the ports, a fresh charge of fuel injected into the cylinders.

It will be observed that with the relative 30 positions of the connections of the connecting rods to the crankshaft, wherein the connection of the connecting rods of the movable cylinder is offset slightly, the maximum amount of efficiency will be obtained as the pull of the rods 14 is not directly opposed 35 to the downward force of the rod 24. The greatest force is applied as the explosion occurs and with this connection in the position shown in Figure 3 the upward pull will be instantly exerted on the crankshaft with the best possible leverage. This arrangement 40 also aids in the exhaust as it permits both the movable cylinder and the movable piston to travel in the same direction for a short distance at the end of the exhaust 45 stroke or when the points are moving from the position shown in Figure 4 to that shown in Figure 5. In these views it will be observed that when the connecting rods 14 are 50 at the upper end of their stroke the connecting rod 24 will be a short distance from the lower end of its stroke and as it moves the remainder of the distance, the connecting rods 14 also start on their downward movement 55 so that both are moving downward at

the same time and while the gases are being exhausted.

The angle of offset in the drawings is shown as 30 degrees however it will be observed that the connection may be offset to 70 any suitable angle.

Having thus fully described the invention, what I claim as new and desire to secure by Letters Patent, is:—

1. In a two cycle internal combustion engine, a cylinder, a movable cylinder forming a piston with a combustion chamber within the said cylinder, an inner movable piston within the said movable cylinder with another combustion chamber formed between 80 the end of the inner piston and the movable cylinder head, suitable connections between the said piston and movable cylinder to a common crankshaft, with the connection of the inner piston approximately 150 degrees 85 from that of the movable cylinder so that the pistons are not opposed, an enlarged cylinder, an enlarged piston depending from the said movable cylinder, an auxiliary chamber connected to the said intake ports 90 and means for connecting the said auxiliary chamber to the said enlarged cylinder, said cylinders having a common intake port for both inner and outer cylinders and exhaust ports, and said movable cylinder having one 95 intake and one exhaust port both corresponding with the intake and exhaust ports of the outer cylinder, and means connecting the said ports to the said enlarged cylinder.

2. In a two cycle internal combustion engine, a movable piston within a movable sleeve piston, an outer cylinder, an enlarged cylinder, an enlarged piston depending from the said sleeve piston, connections between the said pistons to a common crank shaft 105 with the connection of the inner piston approximately 150 degrees from that of the movable cylinder so that the pistons are not opposed, intake ports to said outer cylinder and to said sleeve piston, intake ports in 110 said sleeve piston, exhaust ports in said cylinder and sleeve piston, the said intake and exhaust ports of the said inner and outer cylinders corresponding, and the said intake and exhaust ports of the said movable cylinder corresponding with the intake and exhaust ports of the said outer cylinder, an explosive chamber within the outer cylinder, another explosive chamber within the said sleeve piston and above said inner movable piston, an auxiliary chamber connected to the said exhaust ports and means for connecting the said auxiliary chamber to the said enlarged cylinder, and means connecting the said ports to the said enlarged cylinder.

3. In a device of the class described, a cylinder, a movable cylinder forming a movable piston within the said former cylinder, an inner movable piston within the said

movable cylinder, a skirt depending from the lower end of the said movable cylinder forming a larger piston in another cylinder formed in an enlarged portion at the lower 5 end of the said former cylinder, suitable means for connecting the said movable cylinder and inner piston to a common crankshaft, with the inner piston connection approximately 150 degrees ahead of that of the movable cylinder, said outer cylinder 10 having a common intake port for both inner and outer cylinders and two exhaust ports, and said movable cylinder having one intake and one exhaust port both corresponding 15 with the intake and exhaust ports of the outer cylinder.

4. In a device of the class described, a cylinder, a movable cylinder forming a movable piston within the said former cylinder with 20 a combustion chamber between the cylinder head and end of the piston, and inner movable piston within the said movable cylinder with another combustion chamber between the inside of the end of the said 25 movable cylinder and end of the inner piston, a skirt around the lower end of the said movable cylinder forming another piston in another cylinder formed in an enlarged portion in the lower end of the said 30 former cylinder, said cylinder having a common intake port for both inner and outer cylinders and exhaust ports, and said movable cylinder having one intake and one exhaust port both corresponding with the intake and exhaust ports of the outer cylinder.

5. In a device of the class described, a cylinder, a movable cylinder forming a movable piston within the said former cylinder, an inner movable piston within the said 40 movable cylinder, said pistons and cylinders forming two explosion chambers, said stationary cylinder having a common intake port for both cylinders and two exhaust ports, and said movable cylinder having one 45 intake and one exhaust port, both corresponding with the ports of the stationary cylinder, a skirt around the lower end of the said movable cylinder forming another piston in another cylinder formed in an enlarged portion in the lower end of the said 50 former cylinder, suitable means for connecting the said pistons to a common crankshaft with the inner piston connection to the crankshaft approximately 150 degrees from 55 that of the said movable cylinder, suitable intake and exhaust ports, and means for igniting the gases in the said cylinder.

WILLIAM E. EWART.
